CLAIM

The ornamental design for a breast cancer testing device as shown and described.

DESCRIPTION

FIG. 1 is a front, bottom, right perspective view of a first embodiment of a breast cancer testing device showing my new design;

FIG. 2 is a bottom plan view thereof;

FIG. 3 is a top plan view thereof;

FIG. 4 is cross sectional view cut along the line 4-4 of FIG. 3; and

FIG. 5 is a front elevational view thereof wherein the cover is removed.

FIG. 6 is a front, bottom, right perspective view of a second embodiment of a breast cancer testing device showing my new design;

FIG. 7 is a bottom plan view thereof;

FIG. 8 is a top plan view thereof;

FIG. 9 is cross sectional view cut along the line 9-9 of FIG. 8; and,

FIG. 10 is a front elevational view thereof wherein the cover is removed.

The broken lines illustrating portions of the breast cancer testing device form no part of the claimed design.
